(57) **CLAIM**

The ornamental design for a valve tap, as shown and described.

DESCRIPTION

The file of this patent contains at least one drawing/photograph executed in color. Copies of this patent with color drawing(s)/photograph(s) will be provided by the Office upon request and payment of the necessary fee.

1. Valve [tap]

1.1 : front/side perspective view

1.2 : front elevation view

1.3 : rear elevation view

1.4 : right side elevation view

1.5 : left side elevation view

1.6 : top plan view

1.7 : bottom plan view

The present valve has a light-gold appearance; the handle and the valve body have a special surface finish, while a shiny small band is positioned between the handle and the valve body.
